UNITED STATES PATENT OFFICE.

JOHN F. O'CONNOR, OF CHICAGO, ILLINOIS, ASSIGNOR TO WILLIAM H. MINER, OF CHAZY, NEW YORK.

SIDE BEARING FOR RAILWAY-CARS.

1,360,782.

Specification of Letters Patent.

Patented Nov. 30, 1920.

Application filed June 6, 1919. Serial No. 302,249.

To all whom it may concern:

Be it known that I, JOHN F. O'CONNOR, a citizen of the United States, residing at Chicago, in the county of Cook and State of Illinois, have invented a certain new and useful Improvement in Side Bearings for Railway-Cars, of which the following is a full, clear, concise, and exact description, reference being had to the accompanying drawings, forming a part of this specification.

My invention relates to improvements in side bearings for railway cars.

The object of my invention is to provide a simple, efficient and gravity centering side bearing.

In the drawing forming a part of this specification, Figure 1 is a longitudinal section through parts of car bolsters with my improved side bearing mounted in connection therewith. Fig. 2 is a horizontal sectional view taken on line 2—2 of Fig. 1. Fig. 3 is a vertical sectional view taken on line 3—3 of Fig. 2.

Referring to the drawings, 10 denotes the underside of a body bolster of a railroad car, 11 the upper portion of an opposed truck bolster, A a retaining member or housing of the anti-friction bearing, B the anti-friction element proper and C—C supporting pendulums for the anti-friction element B.

In the drawing I have shown the bearing as attached to the body bolster, and, as shown, the retaining member A is of substantially hollow rectangular form having side walls 12—12, end walls 13 and corner lugs 14—14 by which it is riveted or otherwise secured to the body bolster. On its interior the member A is preferably provided with inwardly extending shelves 15—15 so positioned as to securely clamp and hold in place a filler plate 16, the latter preferably carrying a hardened insert 17 upon which the bearing of the anti-friction element directly takes place.

The anti-friction element B, as shown, is of rocker type and has upper bearing surface 18 and concentric lower bearing surface 19, the latter obviously being adapted to bear directly upon the truck bolster, although normally slightly spaced therefrom as is the upper bearing surface 18 normally slightly spaced from the plate 17. In each end, the element B is formed with an overhanging flange indicated at 20, having a

curved recess on its under side, as indicated at 21, adapted to form a pivotal bearing for the element B on the pendulums C. This is shown most clearly in Figs. 1 and 3.

The pendulums C, which are two in number, one on each side of the element B, are of like form and a detailed description of one will suffice. As shown, each pendulum C comprises a vertical extension 22 having a round upper edge indicated at 23 which fits 60 the corresponding bearing surface of the anti-friction element B so as to pivotally support the latter. On its outer side, each member C is formed with a vertically elongated lug 24 having a round lower edge, as 65 indicated at 25, the latter having pivotal support at the bottom of a recess 26 formed in the side wall of the retaining member A, the side walls having ledges or shelves 27, as indicated in Fig. 3, to sustain the weight 70 of the pendulums C. Below the points of pivotal support of the pendulums C on the member A, said pendulums are formed with heavy-weighted sections of arcuate form, indicated at 28—28. The latter normally 75 have their lower edges disposed slightly above the lower bearing surface 17 of the anti-friction element B.

The operation is as follows: As heretofore explained, the anti-friction element B is 80 normally out of engagement with both the upper and lower bearing surfaces. As the two bolsters approach each other and bring the side bearing into action, it is evident that the anti-friction element B will be lifted 85 slightly with respect to its retaining member A until the upper bearing surface 18 of the element B engages with the plate 17. Relative rotation between the bolsters will then, of course, cause the element B to roll 90 or rock, one extreme position being shown by the dotted lines in Fig. 1. As the element B is thus rolled or rocked, it is evident that its bearing recesses 21 at the tops of the pendulums will force the pendulums to 100 tilt or pivot about their bearing edges 25 until the pendulums assume the position indicated by the dotted lines C' in Fig. 1. To limit the rolling movements of the anti-friction element, the member A may be provided with inwardly projecting lugs indicated at 29 at each end thereof to form suitable abutments for the flat edges 30—30 of the element B. After the parts have been moved to the dotted position shown in Fig. 110

1, and assuming the load removed, the weight of the anti-friction element B will then be immediately transferred to the tops of the pendulums C and thereafter there will 5 be combined pivotal movement of the pendulums C about their bearings 25 to a vertical position and a simultaneous swinging of the anti-friction element B about its pivotal bearings on the tops of the pendulums 10 C. In this way, all the parts will be returned to central or normal position without the aid of any springs or other devices likely to get out of order.

I claim:

15 1. In an anti-friction bearing of the character described, the combination with a hollow retaining member, of an anti-friction element mounted within said member and having upper and lower bearing surfaces 20 normally out of engagement with their corresponding coöperating bearing surfaces, and gravity influenced means pivotally supported on said retaining member, said anti-friction element being in turn pivotally suspended from said means above the pivotal support between said means and the retaining member.

2. In a side bearing for railway cars, the combination with a retaining member having 30 an interior bearing surface; of pendulums

pivotaly supported from said retaining member; and an anti-friction member pivotaly suspended from said pendulums above the points of pivotal supports of the latter, said anti-friction member extending above the pendulums to engage said bearing surface and below the pendulums to thereby adapt it for engagement with an opposed bearing surface.

3. In a side bearing for railway cars, the combination with a hollow retaining member adapted to be secured to the under side of a body bolster, said member having an upper bearing surface on the interior thereof; of a pair of pendulums pivotally supported on the opposite interior sides of said retaining member; and an anti-friction element pivotally suspended from the upper ends of said pendulums above the points of pivotal supports thereof on the retaining member, said anti-friction element extending both above and below the pendulums and thereby adapted to engage the bearing surface of the retaining member and an opposed bearing surface.

In witness that I claim the foregoing I have hereunto subscribed my name this 28th day of May, 1919.

JOHN F. O'CONNOR
